US0D1088023S

(12) United States Design Patent (10) Patent No.: US D1,088,023 S
 Park (45) Date of Patent:  Aug. 12, 2025

(54) DISPLAY PANEL OR PORTION THEREOF WITH GRAPHICAL USER INTERFACE

(71) Applicant: CLO Virtual Fashion Inc., Seoul (KR)

(72) Inventor: Mi Seon Park, Seoul (KR)

(73) Assignee: CLO Virtual Fashion Inc., Seoul (KR)

() Term: 15 Years

(21) Appl. No.: 29/858,887

(22) Filed: Nov. 4, 2022

(30) Foreign Application Priority Data

Aug. 23, 2022 (KR) 30-2022-0034297

(51) LOC (15) Cl. 14-04

(52) U.S. Cl.

USPC D14/486

(57) CLAIM

The ornamental design for a display panel or portion thereof with graphical user interface, as shown and described.

DESCRIPTION

1 Claim, 1 Drawing Sheet
